UNITED STATES PATENT OFFICE.

OSCAR BROPHY, OF PHILADELPHIA, PENNSYLVANIA.

INDUCTION FURNACE

Application filed October 13, 1920. Serial No. 416,694.

To all whom it may concern:

Be it known that I, OSCAR BROPHY, a citizen of the United States, residing in the city and county of Philadelphia, State of Pennsylvania, have invented a new and useful Induction Furnace, of which the following is a specification.

My invention relates to induction furnaces comprising a magnetizable core structure with which are associated the primary or energizing circuit and a secondary circuit in the form of a single turn of molten metal or other conducting material.

My invention resides in a furnace of the character referred to in which the transformer is of the so-called "core" type, the same being a simple rectangle or other closed or substantially closed figure, (as distinguished from the shell type of transformer such, for example, as illustrated in my prior Patent No. 1,296,752,) the secondary encircling a limb of the core, the same limb upon which a primary winding is disposed, the secondary being in communication with the main bath above, and the refractory material being grooved or channeled for this purpose, in such manner as to leave a single portion of the secondary isolated by the refractory material from the main bath.

My invention resides in the furnace structure hereinafter described and claimed.

For an illustration of one of various forms my invention may take, reference may be had to the accompanying drawing, in which:

Fig. 1 is a vertical sectional view of a furnace embodying my invention.

Fig. 2 is a vertical section on the line 2—2 of Fig. 1.

Fig. 3 is a horizontal sectional view, partly in plan, on the line 3—3 of Fig. 1.

Referring to the drawing, within a suitable metal casing 1 supported upon pivots or trunnions 2 is disposed suitable brick-work 3, or equivalent, forming the more or less permanent housing for the refractory material 4 forming the main basin or bath 5, from whose bottom 6 is a downwardly extending channel 7 which, as viewed in Fig. 3, is circumferentially discontinuous between the points 8 and 9.

Built in the refractory material is the laminated core 10 in the form of a simple

rectangle or other simple closed or substantially closed figure. Disposed upon the core 10 in any suitable way, though preferably around the vertical limb 11 thereof, is the primary winding P connected to any suitable source of alternating current of suitable frequency and voltage. The secondary is indicated at 12, 13 as a circumferentially closed molten metal path surrounding or coaxial with the primary P; communication between the part 12 of the secondary, that is, between the part which lies between the points 8 and 9 of the channel 7, Fig. 3, is not direct with the bath 5 through channel 7, because of the presence of the core 10 and the refractory material on either side thereof. At 12 it will be noted that the thickness in a radial direction of the secondary 12 is greater than at 13, where the thickness may be substantially the same as that of the downwardly extending channel 7. The portions 12 and 13 of the secondary, however, are preferably of the same and constant cross section throughout the circumference of the secondary, though varying in shape of cross section due to their different positions. As indicated, the part 12 communicates with the channel 7 by upwardly extending tapering channel connections 14.

The current induced in the secondary 12, 13 maintains its temperature above the melting point, the heat so furnished maintaining also the bath 5 in molten condition.

Without reaction of different parts of the secondary upon each other, due to the current therein, or without other effect of the secondary current solely, circulation is effected as between the secondary proper and the bath 5 by reaction between the current in the primary P and that in the secondary 12, 13 due to repulsion.

By the structure described, a simple "core" type transformer is employed, the secondary being horizontal and surrounding a limb of the core, while maintaining communication through a part of the circumference of the secondary with the main bath, and notwithstanding restriction of height of part of the secondary, its radial thickness may be made anything suitable or desirable, as for example, to maintain constant the cross section of the secondary proper.

While in the example of my invention illustrated the furnace is of the pivoted or tilting type, the same being pivoted upon the trunnions 2 to pour from the lip 15, it will be understood that my invention is equally applicable to stationary furnace structures.

What I claim is:

1. Induction furnace structure comprising a bath, a circumferentially incomplete channel extending downwardly from the bottom of said bath and having a single opening therein, a transformer of the "core" type having a portion of the core structure 10 extending through said opening, and a circumferentially complete secondary surrounding a portion of said core structure and communicating through said channel with said bath.
2. Induction furnace structure comprising a bath, a circumferentially incomplete channel extending downwardly from the bottom of said bath and having a single opening therein, a transformer of the "core" type 15 having a portion of the core structure extending through said opening, a circumferentially complete secondary surrounding a portion of said core structure and communicating through said channel with said bath,
3. Induction furnace structure comprising a bath, a circumferentially incomplete channel extending downwardly from the bottom of 20 said bath and having a single opening therein, a transformer of the "core" type having a portion of the core structure extending through said opening, a circumferentially complete secondary surrounding a portion of said core structure and communicating through said channel with said bath,
4. Induction furnace structure comprising a bath, a circumferentially incomplete channel extending downwardly from the bottom of said bath and having a single opening therein, a transformer having a portion of the 25 core structure extending through said opening, and a circumferentially complete secondary surrounding a portion of said core structure and communicating through said channel with said bath,
5. Induction furnace structure comprising a bath, a circumferentially incomplete channel extending downwardly from the bottom of said bath and having a single opening therein, a transformer having a portion of the 30 core structure extending through said opening, a circumferentially complete secondary and a primary encircling the same limb of said core structure, said primary and secondary being so disposed that by reaction of primary and secondary currents upon each other the molten secondary material is circulated.
6. Induction furnace structure comprising a bath, a circumferentially incomplete channel extending downwardly from the bottom of said bath and having a single opening therein, a transformer of the "core" type having a portion of the core structure extending through said opening, a circumferentially complete secondary and a primary encircling the same limb of said core structure, said primary and secondary being so disposed that by reaction of primary and secondary currents upon each other the molten secondary material is circulated.
7. Induction furnace structure comprising a bath, a circumferentially incomplete channel extending downwardly from the bottom of said bath and having a single opening therein, a transformer of the "core" type having a portion of the core structure extending through said opening and having a substantially vertical limb beneath said bath, and a circumferentially complete secondary and a primary encircling said vertical limb and so disposed with respect to each other that by reaction of the primary and secondary currents upon each other the molten secondary material is circulated.
8. Induction furnace structure comprising a primary, a molten secondary, a bath above said secondary and in communication therewith, said secondary and said primary being so disposed with respect to each other that by reaction of the primary and secondary currents upon each other the molten secondary material is forced in a direction parallel to the axis of the primary and into the bath.
9. Induction furnace structure comprising a primary, a secondary adapted to become molten by the current traversing the same, said primary and secondary being substantially concentric, a bath above said secondary and in communication therewith, said secondary and primary being so disposed with respect to each other that by reaction of the primary and secondary currents upon each other the molten secondary material is circulated between said secondary and said bath.
10. Induction furnace structure comprising a primary, a molten secondary, a bath communicating with said secondary, said secondary and said primary being so displaced axially with respect to each other that by reaction of the primary and secondary currents upon each other the molten secondary material is circulated into the bath.
11. Induction furnace structure comprising a primary, a molten secondary, a bath communicating with said secondary, the coupling between said secondary and said primary being decreased so that by reaction of the primary and secondary currents upon each other the molten secondary material is circulated.

of the primary and secondary currents upon each other the molten secondary material is circulated into the bath.

12. Induction furnace structure comprising a primary, a molten secondary, a bath communicating with said secondary, the primary and secondary being so disposed with respect to each other, that the trans-

verse planes, that will substantially divide the primary and secondary into equal parts, ¹⁰ do not coincide.

In testimony whereof I have hereunto affixed my signature this 12th day of October, 1920.

OSCAR BROPHY
